JAMES E. WRIGHT, OF WEST BAY CITY, MICHIGAN, ASSIGNOR OF ONE-HALF TO JOHN M. KELTON, OF BAY CITY, MICHIGAN.

METAL HOOP.

No. 873,114.

Specification of Letters Patent.

Patented Dec. 10, 1907.

Application filed August 15, 1904. Serial No. 220,839.

To all whom it may concern:

Be it known that I, JAMES E. WRIGHT, a citizen of the United States, residing at West Bay City, in the county of Bay and State of Michigan, have invented certain new and useful Improvements in Metal Hoops; and I do hereby declare the following to be a full, clear, and exact description of the invention, such as will enable others skilled in the art to 10 which it appertains to make and use the same.

This invention is an improvement in "open bead metal hoops", one object being the provision of a hoop having a reinforced driving 15 edge, which will not require the amount of metal heretofore necessary in making "closed bead" hoops.

With these and other objects in view, which will appear later in the specification, 20 the invention consists in certain novel features and combinations of parts together with their equivalents, such as will be more fully described hereinafter and particularly pointed out in the claims.

25 In the accompanying drawings, Figure 1 is a view of a barrel equipped with a hoop constructed after my invention, partly broken away to better disclose the structure, Fig. 2 is a perspective view of a portion of a 30 barrel stave showing the hoop in cross section, and Fig. 3 is a cross sectional view through a hoop showing how the bead may be closed in some instances.

As is clearly indicated, the hoop consists of 35 a flat metal band (1), the upper edge of which is formed with an outwardly curved or arched bead (2) which, in the present instance, is shown as being bent in a continuous curve upwardly and outwardly, thence dropping 40 downwardly in an approximately straight line. The free edge (3) of the bead may be turned very slightly inwardly for the purpose of preventing an exposure of the raw edge of the bead, which might prove a disadvantage 45 in handling or transporting receptacles equipped with these hoops, though this inward turn is not essential.

It will be observed that there are no square corners which would impart weakness to the 50 structure and which would crack or break when pressure is applied thereto. Furthermore, by forming an open bead as contradis-

tinguished from a closed bead, a considerable saving of metal is effected when manufacturing the hoops in quantities, as it is obvious 55 that the bead in a "closed" bead hoop requires more metal than an open bead hoop. At the same time, I do not diminish the amount of bearing surface of the hoop band itself on the barrel and obtain just as broad a 60 bearing as is possible with a closed bead hoop. This is a great advantage, since in handling barrels, the bearing contact of the hoop and staves prevents the dislocation of the latter relative to each other, especially when the 65 barrels receive hard blows on their ends, as when being dropped and as a general rule the broader the bearing contact the stronger the barrel.

The bead is arched outwardly from the 70 barrel so that the entire width of the hoop engages the staves as distinguished from those beads which bulge inwardly and engage the staves whereby the hoop is held at an angle to the barrel surface and has a bearing 75 only at its lower edge therewith.

The open bead is shown as substantially hook-shaped in cross section, the hoop being applied to the barrel and pressed down into place on the bilge without bending, closing 80 or distorting the bead, the latter being left open after the hoop has been set in place and forming a driving edge engaged by the driving tool. The turned free edge of the bead prevents the exposure of a raw edge, which 85 would injure the hands of the operator and the ways down which the barrels might be slid.

The closed bead hoops heretofore constructed were devised principally for the 90 small coopers who use the old form of driving tool and mallet, but in large cooperage factories, special machines are available for pressing rather than driving a hoop to place, and with such machines an open bead hoop 95 can be set without closing the bead, whereas a closed bead hoop is almost essential in a cooperage shop not equipped with such special machines. Of course, the closed bead hoops are used in the large factories, but a 100 considerable saving of metal and consequently of expense can be effected by using the open bead hoop disclosed herein.

In practice, I have found that a hoop with

an open bead can be rolled much more cheaply and easily than a closed bead hoop, as in manufacturing the latter a separate rolling is required to bring the free edge of the bead from the position shown in Fig. 2 to the position shown in dotted lines at (3^a) in Fig. 3. By forming an arched open bead, I retain the transverse elasticity or yielding of the flat band (1) while the hoop is being set whereby to permit the hoop to conform to the shape of the barrel. Another advantage attained by the open bead over the closed bead is that in the latter, the ends of the hoop when lapped over to form a splice, will not lie evenly unless a portion of the closed bead on one end of the hoop is flattened out to permit the inner surface of the opposite end of the hoop to lie flat thereupon. With the open bead, however, it is possible to lap the ends of the hoop so that the open bead on one end is received and nests within the open bead on the opposite end, thus avoiding the necessity and extra labor of flattening the bead on one end of the hoop, and making a neat splice which does not project from the surface of the barrel, the bead being continued unbroken circumferentially of the barrel or keg.

In the foregoing, it will be noted that the bead on the hoop remains open after being set to place, but it is obvious that it may be bent to form a closed bead as the hoop is being driven on the barrel, especially when driving tools, such as illustrated in Fig. 1, are used, and in such instances, the force of the driving tool will have the effect of gradually closing down the free edge (3) of the bead in the dotted line (3^a), as shown in Fig. 3, until the free edge engages the outer face of the hoop band and is firmly supported against slipping or curling under, the bead, in such instance being capable of resisting a very heavy driving force, as in the closed bead constructions, without distortion. The closing of the bead so that the free edge engages the outer face of the hoop band is due solely to the predetermined arch given the open bead. Otherwise the free edge might slide down over the outer face of the hoop without affording a firm support for the driving tool. Obviously, if the bead is to be closed during the driving operation, the lapped ends of the hoop can be nested into each other, just as though the bead was to remain open. Nor is the bearing surface of the hoop band reduced when the open bead is being closed, the bead being closed without drawing upon the band. While these hoops are more particularly designed as "bilge" hoops, they may also be used on the chine of a barrel. This hoop can be manufactured either in straight or roll lengths, which may be kept in stock and as much sold from the stock as is desired.

From the foregoing, it is obvious that I have devised a very simple and inexpensive hoop having a hollow unreinforced open bead, which constitutes a driving edge reinforcing or strengthening the hoop and providing for a neat and economical lap or splice where the ends are riveted together.

The bead is given a predetermined shape or roll, that is to say, the bead is of such predetermined conformation that it will not crack or break down under pressure and if the metal will not withstand the pressure applied, the conformation or predetermined shape of the bead is such as to permit it to bend over until the free edge of the bead engages the outer face of the hoop band at such an angle as to prevent a further slipping, bending or curling of the bead, after which a very great pressure can be applied, the bead, in such latter instance, forming a hollow unreinforced arch, and at all times constituting a driving edge to receive and support the driving implement.

Having thus fully disclosed my invention, what I claim as new is—

1. A hoop for receptacles comprising a band, the entire width of which is adapted to lie against the receptacle, and an open unreinforced hollow yieldable curved bead formed along the upper edge of the band and overhanging the outer surface only of the band, the bead being substantially hook-shaped in cross-section and constituting a hollow curved unreinforced driving edge to receive the impact of the driving means, the free edge of the bead normally lying out of engagement with the band.

2. A hoop comprising a flat band and an open, unreinforced, curved, hollow bead formed along the upper edge of the band and overhanging the outer surface only of the band, the bead being outwardly curved and thence projecting downwardly, the extreme free edge of the bead being bent slightly inwardly to avoid an exposed raw edge, the bead forming a hollow curved unreinforced driving edge.

3. A hoop for receptacles comprising a band, and an open unreinforced continuously curved hollow bead, formed along the upper edge of the band and overhanging the outer surface only of the band, the bead extending in a curve upwardly and outwardly away from the receptacle, and thence dropping downwardly, the free edge of the bead being turned slightly inwardly and adapted to be moved toward and forced against the outer surface of the band when driven under heavy pressure, so as to prevent subsequent slipping or curling of the bead, the bead forming a hollow curved unreinforced driving edge.

4. A hoop comprising a flat band, its entire width adapted to lie against the receptacle to which it is applied, and an open un-

reinforced curved hollow bead formed along the upper edge of the band overhanging the outer surface only thereof and normally out of engagement therewith, the depending free edge of the bead adapted to be closed down against the outer face of the band when driven under heavy pressure, so as to prevent subsequent slipping or curling of the

bead which forms a firm hollow unreinforced driving edge.

In testimony whereof I affix my signature, in presence of two witnesses.

JAMES E. WRIGHT.
